UNITED STATES PATENT OFFICE.

TIMOTHY HOLLAND, OF TROY, NEW YORK.

STEAM-BOILER.

SPECIFICATION forming part of Letters Patent No. 278,963, dated June 5, 1883.

Application filed March 9, 1883. (No model.)

To all whom it may concern:

Be it known that I, TIMOTHY HOLLAND, of Troy, in the county of Rensselaer and State of New York, have invented certain new and useful Improvements in Steam-Boilers, of which the following is a full, clear, and exact description.

Reference is to be had to the accompanying drawings, forming part of this specification, in which similar letters of reference indicate corresponding parts in all the figures.

Figure 1 is a sectional side elevation of my improvement. Fig. 2 is a sectional end elevation of the same, taken through the line *xx*, Fig. 1. Fig. 3 is a sectional side elevation of one of the boiler-tubes enlarged. Fig. 4 is a cross-section of the tubes on an enlarged scale.

The object of this invention is to facilitate the generating of steam for heating and power purposes.

The invention consists in a steam-boiler constructed with a shell having transverse flues and pipes projecting outward through the fire-chamber, closed at their outer ends by couplings, valve-disks, and screw-plugs, and provided with interior concentric pipes supported in place by radial pins or skeleton disks. The boiler-shell is provided with a series of projecting pipes arranged to support the top of the inclosing brick-work, whereby the brick-work, supports are made to assist in generating steam, and thus increase the steam-generating capacity of the boiler, as will be herein-after fully described.

35 A represents the brick-work of the furnace. B is the fire-grate, which is supplied with fuel through the door-way or chute C. The smoke escapes to the chimney through the flue R.

40 D is the upright boiler-shell, which rests upon the bridge-wall E of the fire-chamber, and its upper end rises above the brick-work A, and with it is connected the steam-pipe F, through which the steam is conducted to the place where it is to be used.

45 Through the boiler-shell D, just below the top brick-work, A, are formed a number of flues, G, through which the products of combustion pass from the forward to the rear part 50 of the fire-chamber, the said flues passing through the water-space of the boiler, so as

to communicate to the water the heat received from the passing products of combustion.

With the forward and rear walls of the boiler-shell D are connected the ends of a 55 number of pipes, H, the inner ends of which open into the water-space of the shell D. Upon the outer end of each pipe H is screwed a coupling, I, in the middle part of which is formed a tapered or beveled valve-seat, J. 60 Into the valve-seat J is fitted a disk, K, having a correspondingly-shaped edge, and which is pressed into and held in its seat by the plug L, screwed into the outer end of the coupling I.

65 Within each pipe H is placed a smaller pipe, M, open at both ends, and held concentric with the said pipe H by radial pins N, screwed into the said pipe M by skeleton disks or by other suitable means. With this construction 70 the water in the space between the pipes H M will be heated, and will flow back into the shell D, causing the cooler water in the said shell to flow outward through the interior pipes, M, thus producing a circulation. With 75 this construction also, by removing the screw-plugs L, the valve-disks K, and the interior pipes, M, the exterior pipes, H, can be readily cleaned by an instrument inserted through the outer ends of the said pipes.

80 With the boiler-shell D, above the flues G, are connected the inner ends of pipes H', which are provided with interior pipes, end couplings, valve-disks, and screw-plugs in the same manner as the pipes H, and which are 85 utilized to support the top brick-work, A, the outer ends of the said pipes resting upon bars O, laid in the brick-work, as shown in Fig. 1. The products of combustion pass through the spaces between the inner ends of the pipes H' into the space P, surrounding the upper part of the boiler-shell D. The feed-water is introduced into the lower part of the boiler-shell D through the pipe Q. With this construction a large quantity of water in thin 90 sheets will be exposed directly to the action of the heat, so that steam will be generated rapidly and in large quantities.

Having thus described my invention, I claim as new and desire to secure by Letters Patent— 100

1. A steam-boiler constructed with a shell provided with transverse flues, and provided

with pipes projecting outward through the fire-chamber, having their outer ends closed by couplings, valve-disks, and screw-plugs, and having interior concentric pipes, as set forth.

2. In a steam-boiler, the combination, with the boiler-pipes H, of the screw-couplings I, having valve-seats J, the valve-disks K, and

the screw-plugs L, substantially as herein shown and described, whereby convenient access can be had to the interior of the said pipes, as set forth.

TIMOTHY HOLLAND.
